UNITED STATES PATENT OFFICE.

HARRIETTE ENSLEY HODGSON, OF NEW YORK, N. Y.

PORCH FIRE ESCAPE.

Application filed May 6, 1926. Serial No. 107,000.

The objects of this invention are, among others, to provide a fire-escape affording very great facilities of escape to large numbers of persons, the facilities including provisions for both inactive or timid persons and for those of a bold and active disposition, at the same time affording great opportunity for rescue; to provide a fire-escape which is substantially burglar-proof; and to provide a fire-escape which provides very desirable and serviceable porches or porch rooms for the occupants of the apartments of the building, which may be used for sleeping, or outdoor purposes, and which will be safe play places for babies and small children.

In the accompanying drawings illustrating a preferred embodiment of the invention:

- 20 Figure 1 is a front elevation of the fire-escape on the outside of a building;
 Fig. 2 is a vertical section taken on the line 2—2 of Fig. 1, and
 Fig. 3 is a sectional plan view taken 25 through one of the enclosures.

The wall of the building, usually the rear wall, is marked 2, and 3 are window or door openings therein opening into the enclosures of the fire-escape 4.

30 The fire-escape comprises a vertical series of commodious enclosures 5 opposite the several stories of the building. Only three stories are shown in the drawing, but it will be understood that the invention is applicable to buildings of any height.

The sides of the enclosures are formed in whole or in part of a horizontally barred structure 6, or possibly of some equivalent construction which will serve the purposes of the invention. The sides parallel with the wall 2, and also the sides at right angles to such walls, are preferably of such construction, but it should be understood that one or more of the sides may consist in 45 whole or in part of different construction.

An important function of the barred structure 6 is to provide a broad ladder, extending down the fire-escape from the top enclosure to, or sufficiently near to, the ground, to enable many persons to climb down the outside of the fire-escape to safety, and by the same means firemen can swarm up the fire-escape to effect rescues of disabled persons.

55 Each of the enclosures of the fire-escape is provided with window or door openings

in its sides arranged so that persons in the enclosure can gain access to the outside ladder. In the stories above the ground floor, the openings are preferably window openings placed a distance above the floors, and are provided with closures 7, which are preferably in the nature of outwardly opening, double-leaved frames 8 guarded by strong open-work 9. The lower-most compartment has a door 10 similarly designed. It will be understood, however, that the form of these closures may be varied, provided, however, that they constitute sufficiently strong barriers to make it difficult for a burglar to break in, and also that the openings or the closures, or both, be so arranged and designed, that small children cannot open them on the upper floors, or get through them. Each of these closures is provided on the inside with a suitable catch or latch 11 adapted to be readily opened on the inside, but not from the outside, these latches being protected by plates 12 set into the closures, and also cups and flanges 13 on the inner sides of the plates to prevent the latches being released by inserting an arm or an instrument through the openwork and reaching around behind the plate.

The enclosures of the fire-escape have solid floors 14; and the floors above the ground-floor enclosure are provided with trap-door openings, which are closed by trap-doors 15. In order to provide ample exit from each enclosure to the enclosure beneath, two trap-doors are arranged in each of these floors, at points remote from each other, preferably at diagonally opposite corners, and the trap-doors in successive floors are disposed in staggered relation, so that the formation of wells is avoided, there being solid floor beneath each opening in the floor above. These trap-doors are locked by latches 16 operable from above but not from below, so that they can be readily opened to permit of escape downward from floor to floor, but to prevent thieves or others from passing upward through the fire-escape.

Short-ladders 17 are fixedly secured at the trap-door openings, these ladders preferably projecting slightly above the openings and extending downward only part way toward the floor below. The advantage of causing these ladders to terminate at their lower ends a considerable distance above the floors below is to keep the ladders from being

blocked by those slow in their movements, it being necessary either to drop the distance from the foot of the ladder, or else to swing over onto the broad ladders formed by the adjacent barred sides of the enclosures.

The trap-doors are to be painted red so that they can not be overlooked, and they are recessed at their free edges to permit 10 the ladders 17 to extend through the openings.

The top enclosure has a trap-door 18 through its top, to enable persons in this 15 enclosure to escape onto the roof, if this should be more convenient, or if escape should be cut off below. This door has a catch 19 which can be opened from below, but not from above.

The fire-escape structure has suitable corner supports 20, and suitable intermediate 20 verticals 21 uniting the bars and contributing to the support.

An important function of the grille work

is to constitute a baby-guard, preventing all 25 possibility of babies and small children left to play falling off the porches. The bars are, therefore, placed sufficiently close together to keep a child from getting through, this close spacing being entirely suitable, and indeed advantageous, in respect to the 30 use of the structure as a safe ladder.

What I claim as new is:

A fire-escape comprising a series of 35 enclosures on the outside of a building having internal passageways permitting persons to pass downward from one enclosure to another, and trap-doors for said passageways with latches adapted to be readily opened from above but not from below, the fire-escape also having external ladder means, and openings in its sides enabling persons to gain said external means, with closures for said openings and latches for said closures adapted to be readily opened from the inside but not from the outside.

HARRIETTE ENSLEY HODGSON.
